UNITED STATES PATENT OFFICE

2,254,487

FLOOR WAXING APPARATUS

Robert C. McCune, Tacoma, Wash.

Application June 10, 1940, Serial No. 339,717

2 Claims. (Cl. 91—39)

This invention relates to devices for applying a liquid wax or other similar substance to a floor or other flat surface, and has for its objects to provide a device which carries its supply of liquid wax to be applied to the floor within its structure; which prevents the entrance of air therein, thereby preserving the wax in a liquid state; in which the rate of flow of the liquid from the container may be easily and accurately controlled; in which the control valve is closely adjacent the applying device, thereby preventing the wax from contacting the air; which may be easily disassembled for the purpose of cleaning the parts covered with wax which might be hardened by contact with the air; and which is simple and cheap to manufacture, easy to use, and which effectively applies and spreads the wax in an even and efficient manner.

I attain these and other objects by the devices and arrangements illustrated in the accompanying drawing, in which—

Fig. 1 is a side elevation of my improved floor waxing apparatus; Fig. 2 is a vertical section of the upper part thereof; Fig. 3 is a similar view of the lower part thereof; Fig. 4 is an elevation of a part of one of the retaining bars; and Fig. 5 is a plan view of the applying pad.

Similar numerals of reference refer to similar parts throughout the several views.

Referring to the drawing, it will be seen that the main part of my improved floor waxing apparatus comprises a tube 1, which may be about one-and-a-half inches in diameter and about three feet long. The upper end of this tube 1 is provided with a suitable plug 2 permanently secured therein by brazing, or other suitable means, which is provided with a suitable stuffing box 3, through which the control rod 4 passes. Also an inner tube 5, which may be about $\frac{1}{4}$ inch in diameter, is similarly secured to the plug 2, in coaxial position within the main tube 1. An operating handle 6 may be attached to the upper end of the tube 1 and is provided with a hole 7 in which the upper end of the control rod 4 is mounted. An adjusting handle 8 is mounted on the rod 4, and is secured thereto by means of the set screw 9, at a point above the stuffing box 3.

A partition 10 extends across the inside of the tube 1, near its lower end (Fig. 3) and said inner tube 5 is similarly secured to its upper surface. This partition 10 is provided with a central hole 11 through which the control rod 4 passes, and with one or more holes 12 (only one of which

is shown) near its outer edge for the herein-after described purpose.

A second short inner tube 13, which may be considerably larger in diameter than the said tube 5, is coaxially secured to the under side of the said partition 10 and extends therefrom to a second partition 14 and is provided with holes 15 at its lower end. The inner surface of this tube 13 is screw-threaded for a considerable length, and a screw-threaded plug or valve 16 is mounted therein, said valve being secured to the end of the control rod 4. That portion 17 of the lower partition 14 lying under the said plug valve 16 may be dished to conform with the lower surface of the said valve 16 to form the valve seat therefor. An outlet tube 18 extends concentrically down from the valve seat 17. The valve 16 therefore controls the outlet tube 18. A union nut 19 is mounted on the end of the outlet tube 18 to secure the applying pad or foot to the tube 1. A filling orifice 20 is secured near the upper end of the tube 1, said orifice being suitably closed by a lid 21, or otherwise.

The applying pad comprises a block of wood 22 of suitable size and shape, in which a cross-tube 23 is secured, said tube 23 lying in an opening in the bottom of the block 22 and being provided with a short tube 24 extending centrally from the block 22 and screw-threaded at its end to connect with the union nut 19. A pad 25 of sheep skin is clamped on to the block 22 by means of a pair of clamping bars 26 having ears or lugs 27 extending upward therefrom (Figs. 3 and 4), through which a pair of clamping bolts 28 pass, said bolts lying in holes in the upper part of the block 22 and being provided with thumbnuts 29. The block 22 may preferably be grooved along its upper front and rear edges to allow the edges of the sheep skin 25 to be pressed therein by the clamp bars 26. The cross-tube 23 is closed at its ends but is provided with a series of outlet holes 30 along its underside. The sheep skin 25 is also provided with a plurality of holes 31 therein, said holes 31 being arranged so as not to coincide with the holes 30 in the tube 23, as indicated in Fig. 5.

My improved floor waxing apparatus is operated in the following manner: The valve 16 being screwed down onto its valve seat 17 by means of the rod 4, the closure lid 21 is opened and a charge of liquid wax is poured into the receiving orifice 20. This liquid wax fills the annular space between the tubes 1 and 5 and flows through the holes 12 in the partition 10 to fill

the annular space between the tubes 1 and 13 and then flows through the holes 15 to surround the end of the plug valve 16. As soon as the valve 16 is opened by the manipulation of the control rod 4 the liquid wax flows through the outlet tube 18 and into the short central tube 24 to the cross tube 23, which it fills, flowing out therefrom by the small holes 30 to fill the space in which the tube 23 lies and to flow out therefrom by the holes 31 in the sheep skin 25 and thus be spread by the movement of the apparatus on the floor.

The applying pad or foot may be removed from the apparatus by disconnecting the nut 19 from the tube 24 and by loosening the thumb nuts 29 on the bolts 28 to remove the sheep skin 25 from the block 22, thus permitting all the parts in which the wax is likely to be exposed to air to be easily cleaned.

It is, of course, understood that many variations in the details of my apparatus may be made without departing from the spirit of my invention as outlined in the appended claims, for instance, changes may be made in the form of the valve or in its means of operation, or it may be brought down closer to the applying pad, or the pad may be made of felt, cloth, or other suitable substance.

Having, therefore, described my invention, what I claim and desire to secure by Letters Patent is:

1. A floor waxing apparatus, comprising a main outer tube; an inner tube coaxially secured there-

in; an upper plug for the outer tube; a stuffing box for the upper end of the inner tube; a partition near the lower end of said outer tube, to which said inner tube extends; an opening 5 in said partition between said inner and outer tubes; a second partition substantially at the lower end of said outer tube; a screw-threaded tube coaxially mounted in said outer tube between said first and second partitions; an opening 10 in the side of said screw-threaded tube, the space between said outer tube and said inner tubes forming a compartment adapted to receive liquid wax; a delivery pipe secured to said second partition and communicating with the interior of said screw-threaded tube; a screw-threaded valve engaging the threads in said tube, and controlling the entrance to said delivery pipe; a control rod secured to said valve and passing coaxially upward through said inner tube 15 and stuffing box, whereby said valve may be turned; and means removably secured to said delivery pipe and adapted to receive the liquid wax therefrom and to spread it on the floor.

2. A floor waxing apparatus, comprising a block; a groove in the under side of said block; a cross-pipe mounted in said groove and having outlet holes in its lower wall; a central pipe 20 communicating with said cross pipe and adapted to be removably attached to a liquid wax delivery pipe; an applying pad on the under side of said block; and means for releasably clamping said pad to said block.

ROBERT C. McCUNE.
